UNITED STATES PATENT OFFICE.

LUCIAN A. BROWN AND HUBBARD BIGELOW, OF HARTFORD, CONNECTICUT, ASSIGNEES
TO HENRY K. W. WELCH.

CHURN.

Specification of Letters Patent No. 9,311, dated October 5, 1852.

To all whom it may concern:

Be it known that we, LUCIAN A. BROWN and HUBBARD BIGELOW, both of the city and county of Hartford and State of Connecticut, have invented certain new and useful improvements in Churns, which we do not believe have been known or used prior to our invention thereof; and we do hereby declare that the following is a full and exact description of the same, reference being had to the accompanying drawings, letters, and figures, whereof like letters denote like parts of all the figures, as forming parts of this specification, and wherein—

15 Figure 1 is a perspective elevation. Fig. 2 a perspective view representing the tub with its axes in a horizontal position. Fig. 3 a perspective side elevation of the shaft, fans and beaters. Fig. 4, a vertical sectional elevation of the tub, fans, shaft, and other parts to be described, and as detached from the framework. Fig. 5 a view of the combination of gear, for the movements of fans.

25 The nature of our invention consists in the construction of the churn in such a manner as to increase the agitation of the cream to be converted into butter, and the adaptation of the churn for "working" the butter 30 after being made, or, in other words, extracting the buttermilk and watery parts extant in butter, thereby rendering it more compact and "firm", and less liable to become "rancid."

35 Having thus defined the objects of our improvements we proceed to explain the construction and operation of our machine.

A A Fig. 1 is a framework constructed of any desirable material and form;—B, B, 40 are two standards or supports, bolted or screwed firmly to the frame A, A, with holes c, c, made through each, near the apex, for the reception of the journals d, d, projecting from two opposite points on the periphery of the conical tub E, by which arrangement the said tub may swing or oscillate.

45 F is a barrel, fastened diametrically across the upper or open end of the tub E to its 50 edge, in any convenient and practicable manner. The object of this diametrical

barrel is to form a support for the upper portion of the shaft, G, G, to which, under the bar F, is attached a fan or beater H and over the same bar the crank I. On the inner 55 side of the tub E is fastened to its bottom, watertight, a conical tube K, the upper end, only, of which is seen in the figure under consideration, but more distinctly seen in Fig. 4, to which reference will be made 60 presently, for explanation of other parts, in connection with this.

L L, is a fan or beater attached to a hollow or cylindrical shaft, not seen in this figure.—m, m, m is a bale or fork, suspended 65 upon two pins, on the bridge n, n, which is fastened to a crossbar on the bottom of the tub E, not seen in this figure. On the projection or handle of the fork m, m, m, is a hole at p, whereby it may be held in its appropriate places, as occasions require, upon the pins o, o, on the frame A, A.

Now, in order to a full comprehension of the construction and operation of this machine, we must call attention to Figs. 4 and 75 5 for the explanation of parts not seen in Fig. 1.

Fig. 4 is a vertical elevation of the tub E and its appendages, detached from the framework A A and stands B, B, Fig. 1. 80

F is the diametrical crossbar fastened to the upper or open end of the tub E.

q q is another crossbar, fastened diametrically across the bottom of the tub E. n, n, is a bridge screwed or otherwise secured fast 85 to q q.

m, m, m is a fork or bail connected with the bridge n, n, by suspension on pins r r, projecting from the bridge and passing through holes in the fork, so loosely that 90 the fork may swing upon the pins easy.

S, S, is a shell with inside gear, fastened to the lower end of a shaft, G G, which end passes through said gear and rests in a step or hole in the bridge n n, as its support,— 95 the upper end of the same shaft is sustained in its place by passing through the bar F, or through boxes fastened to it. To this shaft G, G, is attached the fan or beater H, H, H.

t is a spur gear attached to a hollow or cylindrical shaft x x, which passes over or 100

- around the shaft G G, upon this shaft $\alpha \alpha$ is turned a "neck", just above the gear t , for the purpose of a journal to run in the crossbar $q q$, with a cap y, y , over it, and forming one half of the bearing for said neck;—the upper end of this shaft $\alpha \alpha$ is supplied with a bush, or other convenient arrangement, whereby it may be supported by the shaft G G, around which it revolves.
- 5 To the upper end of $\alpha \alpha$ is secured a fan or beater L L, L. The hollow shaft $\alpha \alpha$, with G G within it, revolves within a conical tube K, which may be made of tin, or any other suitable material, and fastened watertight to the inside of the bottom of the tub E, and should reach very near the underside of the beater L, L, L. This tube K should be fastened watertight to prevent escape of cream.
- 10 V is a pin or stud, fastened to the crossbar $q q$ for the support of u , a small gear or pinion, which connects the movements of the shell gear S, S, on the shaft G G with the spur-gear t on the shaft $\alpha \alpha$ in manner
- 15 as seen in Fig. 5.
- 15 From this description, to return to Fig. 1, it is obvious that when, now, the hand is applied to the crank I, motion will be communicated to the shaft G G and all its attachments. The shell gear, now, by revolving the stud gear or pinion u , communicates motion to the spur gear t , and with it the conical shaft $\alpha \alpha$ and beater L, L, L, in an opposite direction. It will thus be seen, how, the cream being contained in the tub E, occupying the space between its inner side and periphery of the conical tube K, in which space also the fans H and L revolve in opposite directions to each other, 20 the agitation of the cream is effected. Continuing, then, this agitation, by rotating the crank I, the butter will "come" in a short space of time.
- 25 We will here remark that we find it necessary to cover the tub during the operation of making butter, to prevent the spattering of cream. This however is not indicated in the figure, but we employ a circular cover, made in two parts, each covering half of the 30 opening of the tub, and one of which is represented at Z, Z, Z, Fig. 2. We will also remark that while our machine is employed for making butter, that the tub E is in a vertical position, as represented in Fig. 1,
- 35 and sustained in that position by the fork $m m m$ resting upon the pin on the top of the frame A A as seen in the figure.
- 40 When the butter is "come" we lift the fork $m m m$, off the pin o , and having placed any convenient receptacle for the buttermilk in a desirable position, we gradually elevate the lower end of the tub E, which swing upon the journals d, d , to about 45 90 degrees from its vertical position, when the buttermilk will find egress through the

aperture a' in the cover Z, Z, Z, as seen in Fig. 2, which now represents the tub E in a horizontal position. It is apparent that this arrangement saves lifting and labor, in the operation of pouring off the buttermilk, 50 and enables the dairy maid to perform a task with ease, which, in large churning, would require the assistance of a male's stronger muscles, as well as conduced to the saving of buttermilk and to cleanliness.

55 This horizontal position of the tub E is maintained by swinging the fork m, m, m , over on its bearings 90 degrees, which its own gravity generally performs and resting it by the hole p , upon the pin o on the side or edge of the frame A A as seen in Fig. 3.

60 The cover Z, Z, Z, Fig. 2, is kept in its proper place by what we term a yoke b, b , which is simply pushed in between the top of the said cover and underside of the bar F, 65 or any other convenient mode. In this horizontal position of the tub E we continue the rotation of the crank I, as in the operation of churning, and the butter thus becomes kneaded, worked and rolled, as the beater H 70 in its revolutions scrapes the butter from the inside of the tub, while the beater L, revolving in the opposite direction, in close proximity to and inside of the other, will strike the butter forced over the beater H by 75 the accumulation by scraping off the butter on the side of the tub, while the buttermilk and water, extracted from the butter by this process, runs down over the now inclined bottom of the tub E, and escapes by the 80 aperture a' of the cover Z, Z, Z, into any receptacle placed under the aperture to receive it.

85 We find, in our experience, that the relative velocity of the two fans H and L is an item of importance, and that the proportion of 2 (two) of the fan H to three of the fan L has been attended with the best results. This is probably owing to the smaller periphery described by the inside 90 fan, so far as the operation of churning is concerned, but in relation to working of butter, the relative velocities of the fans or beaters affects the result, by the different and differing points at which the beaters meet 95 in their respective revolutions and the law of gravity acting upon the lump of butter. A certain relative velocity of the beaters to each other will catch the lump of butter and work and roll it oftener in a given 100 number of revolutions, than with a different relative velocity of the beaters to each other in the same number of revolutions. This is a fact only learned by experiments, and corroborated by their repetition.

105 Having thus described our apparatus and its operation, what we claim as our improvement and invention, and desire to secure by Letters Patent is—

110 The combination of the tub E, including

the appendages described, with the frame
A A and stands B, B, or any other conven-
ient frame work adapted to the use of the
tub in a vertical and a horizontal position,
5 but in manner and for the purposes sub-
stantially as herein set forth and described.

In testimony whereof we have hereunto
set our signatures this twelfth day of April

A. D. one thousand eight hundred and fifty-
two.
